UNITED STATES PATENT OFFICE.

DANIEL C. STOVER, OF FREEPORT, ILLINOIS.

IMPROVEMENT IN WINDMILL-REGULATORS.

Specification forming part of Letters Patent No. 145,765, dated December 23, 1873; application filed August 13, 1873.

To all whom it may concern:

Be it known that I, DANIEL C. STOVER, of Freeport, in the county of Stephenson and State of Illinois, have invented an Improved Windmill-Regulator; and I do hereby declare that the following is a full, clear, and exact description thereof, reference being had to the accompanying drawings making part of this specification, in which—

Figure 1 is a vertical section through the upper portion of a windmill, showing part of the wind-wheel and vane. Fig. 2 is a sectional view, illustrating my improvement for governing the mill. Fig. 3 is a top view of Fig. 1.

Similar letters of reference indicate corresponding parts in the three figures.

This invention relates to an improvement for regulating automatically that class of windmills the vanes of which are pivoted to the caps of the mill in such manner as to swing horizontally and change the faces of the wind-wheels, so that they will "edge" more or less to the wind, according to the force thereof. My object is to employ, in combination with a windmill of the description above named, and with the pump thereof, a chamber which communicates with the interior of the pump above the piston, and in which is a piston whose rod is connected with a gravitating-arm, to which the vane of the mill is attached, so that the surplus water, or that which cannot escape through the pump-nozzle, shall operate to regulate the speed of the mill, as will be herein-after explained.

The following description of my invention will enable others skilled in the art to understand it.

In the accompanying drawings, A represents the cap of the mill-tower, through which passes a hollow turning-center, B, the upper end of which is flanged and supported upon anti-friction balls *h*. On this center B is formed a bearing, G, through the tubular portion of which passes the shaft of the wind-wheel E, on the inner end of which shaft is keyed a crank-wheel, *e*. To a wrist-pin on the crank-wheel *e* is attached a rod, *f*, the lower end of which is connected to the upper end of a short grooved rod, C, by a pivot, *g*. The lower end of this grooved rod C has a ball, *c*, formed on it, which is received into a socket formed on

the upper end of the pump-rod D, and through which a hole is made vertically. The rod D passes down into a pump-stock, P, and has a piston or valve-bucket, *t*, secured to it, for raising water and forcing it out of cock or nozzle *r*. The pump rests on a platform, R, and alongside of it is a vertical surplus-water cylinder, N, which communicates with the interior of the pump above the piston *t* by means of a passage, *y*, as shown in Fig. 2. The cylinder N is open at its bottom and closed at its top, except the passage *y*, leading into the pump; and inside of this cylinder is a piston, *m*, the rod *l* of which rises through the cylinder, and has connected to it a rope or chain, *k*, which passes up, through the rod C and turning-center, to and over a pulley, *i*, on bearing G, and is attached to an arm, W. This arm W is pivoted at *j* to the bearing G, and its outer end carries an adjustable weight, W'. F represents the vane of the mill, which is pivoted at *s*, (see Fig. 3,) so as to swing horizontally. This vane is connected to the vertically-vibrating gravitating-arm W by means of a rod, *p'*, which is pivoted at *q* *p*. Other means than those above described may be adopted for connecting the vane to the piston-rod *l*, although for simplicity I prefer these means.

It will be seen from the above description that when the speed of the mill is so great as to raise more water than can pass through the cock *r* the surplus water will flow into the cylinder N above the piston *m*, and by the weight of this water and the force of the piston *t* the piston *m* will descend, carrying with it the rod *l* and raising the loaded arm W more or less. The effect of this descent of the piston *m* is to change the angle of the vane F with respect to the face of the wind-wheel E and retard the speed of the mill. If the force of the wind is such as would be liable to break or derange the mill-works or the pump, then the piston *m* will be forced so low as to move the vane around parallel to the face of the wind-wheel, as indicated in dotted lines, Fig. 3, and thus throw the wind-wheel out of the wind.

By means of the cock *r* the discharge from the pump can be regulated or entirely shut, in which latter case the mill will stop.

It is obvious that my invention is applicable

to double-acting pumps, as well as to the single-acting kind.

I am aware of the patent of Walter S. Peck, granted June 19, 1860, which shows an atmospheric governor, consisting of an air-pump with regulating-cock, for controlling the vanes of a wind-wheel, and therefore I do not claim, broadly, a pump for controlling the vanes of a wind-wheel; but

Having described my invention, what I claim

as new, and desire to secure by Letters Patent, is—

A surplus-water cylinder, N, communicating with the interior of a pump, and having a piston working in it which is connected to a vane-working mechanism, substantially as described.

DANIEL C. STOVER.
